UNITED STATES PATENT OFFICE.

WILLIAM ILE, OF JACKSON, MICHIGAN.

CAP AND SHELL FASTENING FOR LAMP-SOCKET CASINGS.

Application filed July 2, 1925. Serial No. 41,207.

The invention relates to a cap and shell fastening for lamp socket casings.

The object of the present invention is to improve the construction of cap and shell fastenings for lamp socket casings and to provide a simple, practical and efficient fastening means for securing the cap to the shell of a lamp socket casing of strong durable and comparatively inexpensive construction designed for use on either key or keyless sockets and adapted to afford a maximum amount of strength for resisting separation of the cap and shell and capable of effectually preventing the same when locked from being separated without breaking the metal of the fastening means.

A further object of the invention is to provide a cap and shell fastening of this character adapted to enable lamp socket casings to sustain considerable weight without impairing the fastening means.

With these and other objects in view, the invention consists in the construction and novel combination and arrangement of parts hereinafter fully described, illustrated in the accompanying drawing and pointed out in the claims hereto appended, it being understood that various changes in the form, proportion and minor details of construction, within the scope of the claims, may be resorted to without departing from the spirit or sacrificing any of the advantages of the invention.

In the drawings:

Figure 1 is a perspective view of a lamp socket casing constructed in accordance with this invention, the cap being shown separated from and elevated above the shell or body portion of the casing.

Fig. 2 is a vertical sectional view of the same, the cap being shown separated from the body portion and properly positioned for interlocking the cap with the shell.

Fig. 3 is a similar view of the cap and shell showing the same interlocked.

Fig. 4 is a horizontal sectional view of the same.

In the accompanying drawing in which is illustrated the preferred embodiment of the invention 1 designates the metallic shell or body portion of the lamp socket casing provided at its upper end which is telescopically engaged by the flange 2 of the cap 3 with bayonet slots 4 preferably four in number and arranged at diametrically opposite points and composed of vertical entrance

branches and horizontal branches extending from the lower ends of the vertical branches. The upper end of the metallic shell is adapted to fit within the flange 2 of the metallic cap 3 which is provided at diametrically opposite points with inwardly extending horizontally disposed resilient tongues 5 formed integral with the cap by partially severing the metal of the flange 2 at the lower edge thereof and bent inwardly to provide an inner arm 6 and having the terminal portion 7 bent outwardly to form an outer arm. The tongues thus consist of inner and outer arms and a connecting portion and the vertical branches of the L-shaped bayonet slots 4 are of sufficient width to permit the tongues 5 to enter the slots when the cap is moved telescopically over the upper end of the shell. This movement of the cap will bring the tongues to the horizontal branches of the slots and the cap is then partially rotated to the right with respect to the shell to carry the tongues away from the vertical branches of the slots 80 into the horizontal branches which are closed at the inner ends as shown. The edges of the tongues will engage with the shell at the upper edges of the slots and will resist any tendency to separate the cap 85 from the shell by moving the parts telescopically or longitudinally without previously rotating the same to return the tongues to the entrance portions of the slots.

The fastening device is thus provided of 90 considerable strength and will enable the lamp socket casing to carry a relatively large amount of weight. The cap and shell are adapted to be readily engaged with each other and disengaged from each other by 95 the said telescopic and rotary movements and in order to prevent accidental rotary movement of the cap or shell the cap is provided with an inwardly extending projection 8 formed by indenting the flange 2 from the exterior and adapted to engage in one of a plurality of perforations 9 formed in the upper portion of the shell and arranged in spaced relation with the bayonet slots. A single projection 8 is provided but an aperture 9 is formed adjacent each of the slots 4 and is arranged in spaced relation with the same so that the cap may be placed on the shell in any position in which the tongues will register with the entrance slots and the single projection 8 will engage the adjacent perforations 9 when the cap is 105 110

partially rotated. In other words the projection 8 of the cap will engage in one of the perforations 9. The cap is released by compressing the shell 1 adjacent the projection 8 and the engaged perforation 9 to disengage the perforation from the projection. This will free the cap and enable the cap to be partially rotated to return the tongues to the entrance branches of the slots and allow the cap to be readily pulled off the shell.

What I claim is:

A cap and shell fastening for lamp socket casings comprising a shell provided with a plurality of slots having approximately vertical and horizontal branches, the vertical branches forming an entrance, a cap having a flange to fit over the shell and pro-

vided with integral tongues having free terminals at one end extending substantially horizontal and being of a length to pass through the entrance portions of the slots and bent inwardly to offset the body portions of the tongues and present their edges for engaging the upper edges of the horizontal branches of the slots, said tongues being carried into the horizontal branches by a partial relative rotary movement of the parts and the free terminals of the tongues being bent outwardly and gripping the shell interiorly thereof at points beyond the horizontal slots, and means for locking the parts against such relative rotary movement.

In testimony whereof I have hereunto set my hand.

WILLIAM ILE.
